UNITED STATES PATENT OFFICE.

THEODORE C. NORTHCOTT, OF LURAY, VIRGINIA.

FLYCATCHER.

1,311,704.

Specification of Letters Patent. Patented July 29, 1919.

Application filed February 23, 1918. Serial No. 218,805.

To all whom it may concern:

Be it known that I, THEODORE C. NORTHCOTT, a citizen of the United States, residing at Luray, in the county of Page and State 5 of Virginia, have invented new and useful Improvements in Flycatchers, of which the following is a specification.

The present invention has reference to fly-catchers; and it proposes, briefly, an improved device of the general class or character stated in which the body portion, or catcher proper, is revolvably connected with the handle in such a way as to permit it to be set and yieldingly retained in any desired 10 angular relation thereto, and with either side in active position, whereby it may be adjusted to contact squarely against a wall, ceiling or other surface, irrespective of the inclination thereof, and will automatically 15 conform itself to such inclination to compensate for any error in its original adjustment.

The invention also resides in the provision of a catcher comprising a strip of wire 20 gauze or the like both surfaces of which are adapted to be coated with a sticky substance similar to that used in the preparation of flypaper. The carrier may be readily reversed, due to its revolvable mounting, 25 to bring either side of the strip outermost and may be easily and quickly detached from the device to permit the gauze strip to be cleaned and re-coated, the foraminous or reticulated construction of the strip enabling 30 the coating to be applied to both sides thereof at a single operation. Other objects and advantages will appear as the description 35 proceeds, and parts of the invention may be used without others, or in other and different environments.

In the accompanying drawing:

Figure 1 is a perspective view of the improved catcher showing the body portion in one position.

Fig. 2 is a part-sectional side elevation, showing the body in a different position.

Fig. 3 is a horizontal section on line 3—3, Fig. 2.

Referring more particularly to said drawing, 5 and 6 indicate, respectively, the body or catcher proper and the handle of the implement, these two parts being connected together by a bail 7.

The first-mentioned or body part 5 consists, in turn, of a skeleton outer member or frame 8, preferably annular in shape,

and a strip 9 of wire gauze or other suitable material of like character. The gauze strip is soldered or otherwise attached along its margin to the annular frame 8, the edges of 60 which are preferably turned inward, as indicated at 10, to provide supports, against one or the other of which the gauze strip rests. The strip 9 forms a perforated partition for the body 5 located to one side of the 65 central diameter of the said body to form trapping receptacles varying in depth for reverse or alternate use and whereby insects of various sizes located on walls, tables or other surfaces or devices may be trapped 70 more readily. The handle 6 may be of any suitable size and character, and, hence, requires no special description, excepting that it is provided at its inner end with a longitudinal socket 13 to receive the twisted stem 75 14 of the bail 7.

The last-named part is likewise constructed of heavy spring wire, and is here shown as substantially Y-shaped, the shank of the Y being formed by the stem 14. The two 80 diverging arms 15 of the bail are turned laterally inward at their free ends, as indicated at 16, said ends being inserted pivot-wise through a pair of diametrically opposite openings 17 formed in the frame 8, so 85 that said frame can be rotated or swung about the said ends as about a pair of trunnions. The portions of the arms 15 adjacent the ends 16 are designed to exert a clamping action upon the frame, so as to hold it 90 in any position into which it may have been turned, the said arm engaging the edges of the frame excepting when the latter and the bail are disposed in co-planar relation, in which case the outer or clamping portions 95 of the bail arms will engage the central portion of the peripheral surface of the frame. The intermediate portions of the bail arms are preferably formed with outwardly directed angular projections 19, which serve 100 to strengthen and stiffen said arms to such degree that they will have ample resilient resistance relatively to the frame to permit the outer or clamping portions to yield slightly during the rotary adjustment of 105 the body, but at the same time effect a sufficient frictional binding action on the frame to obviate too loose movement of said frame during the trapping operation of the latter and to assist in applying the catcher as a 110 whole in different positions relatively to the wall. The annular or circular contour of

the frame and the central engagement therewith of the ends 16 of the arms 15 provide for a balancing of the frame relatively to the arms 15 during the operation of the catcher 5 and also permit the arms 15 to be made comparatively shorter in view of the fact that only one-half of the frame is rotatable between the said arms at one time. The arms 15 by their convergence from the frame also 10 set up the necessary binding action relatively to said frame to obviate too loose movement as hereinbefore specified.

The mode of operation of the implement is believed to be apparent from the foregoing, and, hence, to require no extended description, the body 5 being turned in one direction or the other into the desired position, and then retained in such position by 20 means of the clamping action exerted by the bail arms upon the frame member of the body.

I claim:—

1. An insect catcher comprising an annular body having a perforated partition extending fully over the interior of the same to one side of the central diameter thereof and at a distance inwardly from opposite side edges of the body to provide trapping receptacles of different depths for alternate use, and a spring bail embodying arms loosely and pivotally engaging diametrically opposite portions of the center of said body and having a resilient frictional binding ac-

tion on opposite portions of the edge of the body, the said arms being yieldable laterally 35 to permit rotation of the body within and between the arms to bring different sides of the catcher into operative position without detaching the ends of the bail from the body. 40

2. An insect catcher comprising an annular body having a perforated partition extending over the interior of the same to one side of the central diameter thereof and at a distance inwardly from both opposite side 45 edges of the body to provide trapping receptacles of different depths at opposite sides of the body for alternate use, and a spring bail having arms terminally and loosely and pivotally engaging diametrically opposite 50 portions of the center of said body and converging toward and exerting a clamping action on opposite portions of the annular side edges engaged thereby to hold the body in its adjusted position solely by frictional contact of the arms therewith, the body being rotatable between the arms without requiring detachment of the bail ends from the body. 55

In testimony whereof I have hereunto set 60 my hand in presence of two subscribing witnesses.

THEODORE C. NORTHCOTT.
